AARON GROFF, OF EBURNE, BRITISH COLUMBIA, CANADA.

PAPER-FOLDING MACHINE.

1,201,719.

Specification of Letters Patent.

Patented Oct. 17, 1916.

Application filed April 19, 1915. Serial No. 22,335.

To all whom it may concern:

Be it known that I, AARON GROFF, a citizen of the Dominion of Canada, residing at Eburne, in the Province of British Columbia, Canada, have invented certain new and useful Improvements in Paper-Folding Machines, of which the following is a specification.

This invention relates to a machine for folding the paper serviettes, such as are used in hotels and restaurants for table use. Where a large number of these serviettes are used a considerable amount of work is involved in folding them by hand in a suitable manner, which work the machine, which is the subject of this application, is designed to perform in a rapid and satisfactory manner whereby the serviette may be sold to the hotels, restaurants, etc., in a folded form ready for use.

The invention is particularly described in the following specification, reference being made to the accompanying drawings, in which—

- 25 Figure 1 is a side elevation of the machine complete. Fig. 2 is a section on the line *a—a* in Fig. 3. Fig. 3 is a general plan of Fig. 2 with the paper feed rollers and knives removed. Fig. 4, a section at *b—b* in Fig. 2 of the first fold blade slide and slideway. Fig. 5 is a section on the line *c—c* in Fig. 3 showing the presser plate of the final fold blade. Fig. 6 is a cross section of the same at *d—d* in Fig. 3. Fig. 6^a is a section at *g—g* in Fig. 3. Figs. 7, 8, 9 and 10 show the successive folds of the serviette as imparted by this machine. Fig. 11 is a perspective view of the die of the operative mechanism of the second or quarter fold. 40 Fig. 12 is a plan showing the die in position at the corner of the slideway. Fig. 13 is a section at *e—e* in Fig. 12, and Fig. 14, a section of the same on the line *f—f* in Fig. 12.
- 45 The machine comprises the combination with a suitable frame 2 of a bearing stand 3 surmounting the same and adapted to receive the end of a shaft 4 which is introduced through the tubular core of a roll 50 of paper 5, the roll being centered on the shaft by a cone at each end. A light frictional resistance is applied to the paper roll to check free rotation of it, by a light strip 8 of thin sheet metal, the downwardly projecting arms of which are pivoted at 19 on the base of the bearing stand, and the strip
- is drawn against the roll by a light coiled spring 11 holding the strip against the circumferential surface of the roll of paper. From the roll 5 the band of paper is passed 50 between feed rollers 12 and 13 which are rotatably mounted below it. One of these rollers 12 is in stationary bearings and is driven by a chain or band 14 from a shaft 15 which is driven by suitable means from the first motion shaft 16 of the machine. The bearings of the other roller 13 are free to move toward the drive roller 12 against which it is pressed by light springs 17. From the feed rollers the paper passes downward between the cutting knives 18 and 19 and across a fence plate 25, the depth of which plate 25 below the plane of the knife substantially corresponds to the width of the paper. The movable knife blade 19 is 70 moved toward the other to effect the cut by a quick movement cam 20 on the shaft 15, (see Fig. 2) acting through the intervention of a lever 21 pivotally mounted at 22. This movement is made against the resistance of 80 a spring 23 which returns the knife. Between the feed rollers and the knife blade the paper passes between oppositely concaved guards 24 which provide accommodation for the continuously fed paper while the knife 85 is cutting.
- 90 The fence plate 25 has a slightly tapered right angled fold 26 bent in it across its midlength, into which the cut square of paper 5^a is pressed by a blade 27 to impose the first fold, as indicated by *m* and shown in Fig. 7. This first fold blade is secured, as shown in Figs. 2 and 4, to a base member 28 which is slidable in guides 29. The blade is projected into the fold 26 of the fence 95 by a quick action cam 30 on the shaft 16 acting through the intervention of a lever 31 pivoted at 32 and connected to the slideable base member 28 of the blade by a rod 33, and is withdrawn from the fold by a 100 spring 34. The forward projection and withdrawal of the blade require to be quickly performed, that the blade may be out of the way of the next square of paper as it is delivered from the feed rollers. 105
- 110 The fence fold 26 has a slot 35 across it at the middle, into which slot the half folded serviette, which has been left in the fold 26, is pressed to impose the quarter fold by a blade 36, and after folding, the quarter folded serviette is carried by the same blade 36 which imposed the fold along the exten-

sion of the slot 35 to a triangular slot 37 hereinafter referred to where the final folds are imparted.

The blade 36 by which the quarter fold *n*, as illustrated in Fig. 8, is imposed is endwise projected into the slot 35, is carried lengthwise of that slot to the location 37, and is endwise withdrawn at that place by the following means: Each blade 36 is secured 5 on a stud 38 projecting from the center of a square die block 39, the square sides of which are respectively parallel and at right angles to the leading edge of the blade secured to it and has a square neck 40 the 10 faces of which are disposed diagonally to the square of the die. The blade is secured on the stud by a nut and is retained with its leading edge parallel to one side of the die by a steady pin 41 fitting a corresponding 15 aperture in the blade. A series of these dies with their blades 36 attached, are mounted in a rectangular slideway 42 which is horizontally disposed parallel to the plane of the slot 35. The corners of this slideway 20 are square so that the dies may travel along its sides and ends and maintain the leading edges of the blades always parallel. The dies are moved along the slideway by an endless chain 43 taking around corner sheaves 25 44 30 45 rotatably mounted in the supporting frame beneath the slideway. One of these sheaves 44 is a sprocket wheel and is mounted on a shaft 46 which is driven by bevel gears 47 from a shaft 48 driven by a chain 35 or band 49 from the first motion shaft 16 of the machine.

Each die 39 with its blade 36 is moved along the rectangular slideway by a member 50, see Figs. 12 and 13, which is secured to 40 a link of the chain and is bent around the outer edge of the slideway to engage the after corner of the square neck 40 of the die. For convenience of construction this member 50 may be made in two pieces, as shown. As 45 the contacting corner of the square neck is subject to wear and requires to be nicely adjusted, adjusting pieces 51 may be secured to the sides of the square, as shown in Fig. 11.

To avoid canting of the die while its driving member 50 secured to the chain is turning around the corner sheaves, a light spring 52 is secured in a recess in the bottom of the slideway to project its square free edge slightly above the bottom of the slideway 55 in alignment with the inner side of the next side of the rectangle. As the die approaches the corner of the slideway it depresses the spring and when the die reaches the corner the square edge springs up and retains the die in alignment with the next side of the rectangle while the chain attached member 50 is turning around the quarter circle of the sheaves. With this mechanism each blade 60 65 36, as its die reaches the outer corner of the rectangular slideway, which is toward the

fold 26 of the fence plate, is projected endwise into the cross slot 35 and when the die reaches the corner of the rectangle which is adjacent the fold 26 it travels along that side of the slideway which is adjacent the slot 35 and carries the half folded serviette along the slot 35 to the other end of that slot where at 37 the remaining angular folds *o*, *p*, as shown in Figs. 9 and 10 respectively, are imposed on the serviette. At this place an angular notch 37 of approximately thirty degrees is removed from the cover plate and base plate of the slot 35, the axis of the angle forming a forty-five degree angle with the line of travel, or with the end of the slot.

Pivoted mounted at 53 and 54 below the plane of the slot 35 triangular blades 55 and 56 are mounted to move across the triangular notch 37 in planes that are parallel to that of 35. The pivot pins 53 and 54 of these blades have short levers 57 and 58 secured on them and the ends of these levers are connected by rods 59 to the ends of levers 60 mounted on pivot pins 61, the other ends of which levers are acted upon in parallel planes by quick movement cams 62 secured on the first motion shaft 16. By this mechanism the triangular blades are, one a little in advance of the other, moved across the notch 37 below the plane of the slot 35.

In alignment with the axis of the angular notch 37 a member 63 is mounted in a slideway 66 to move axially into and out of the triangular notch 37, and in the outer end of the slideable member 63 a presser plate 67 is hinged at 68, the free end of which presser plate is shaped to conform to the triangular notch 37. The slideable member 63 is projected into and withdrawn from the notch 37 by a lever 71 pivoted at 72 and connected by a fork or slotted end to a pin 73 in the front end of the slideable member 63. This lever 71 has a small roller on a pin 70, which roller projects into the face groove of a cam 69 secured on a shaft 74 which is driven by a Hook's joint 75 from a shaft 76, which again is driven at the required rate of speed by a chain 77 from the first motion shaft 16. The groove of the cam 69 has a concentric portion that will afford the presser plate 67 a period of rest while it is within the notch 37 and the triangular blades 55 and 56 are folding the opposite corners of the quarter folded serviette over it.

The hinged presser plate 67 has an adjustable spring 78 which tends to hold it in the plane of its movement, and it is lifted against the resistance of this spring to the angular position, as shown in Fig. 5, by a roller on the end of a short lever 79 pivoted at 80 to the slideable member 63, the lower end of which lever projects downward so that at the outward limit of the movement of the slideable member it engages a corner 120 125 130

of the frame of the machine, as shown in full lines in Fig. 5, to lift the presser plate. The pivot is so arranged in relation to the contact of the roller on the lever on the underside of the presser plate that the plate is stably supported until the lever is forcibly thrown down by the lower end of the lever engaging a projection 81 at the inner limit of the presser plate's movement. When the 10 quarter folded serviette has reached the location of the notch 37 and the blade 36 which folded and carried it there is withdrawn, the presser plate 67, angled upward, as shown by the full lines, is projected into 15 the notch 37 the lower end of the lever 79 engages the projection 81 and is thrown down, and the presser plate drops under the action of its spring 78 and its own weight onto the quarter folded serviette and presses 20 it below the lever of the triangular blades 55 and 56 folding the corners upward, as shown by the arrows in Fig. 9. These blades 25 55 and 56 are then moved across the notch 37 and fold the corner pieces over the central portion, as in Fig. 10. The presser plate is then withdrawn and the operation of folding is completed.

Just below the level of the plane of movement of the triangular blades 55 and 56 a light spring 83 projects outward beyond each side of the notch 37 below which springs the presser plate 67 presses the folded serviette so that they are prevented from rising to interfere with the succeeding serviettes. The folded serviettes are pressed by the succeeding ones into a chute 82 which is curved upward to deliver them where they may be bound in bundles for packing.

Although specifically described as imposing the folds illustrated in Figs. 7, 8, 9 and 10 the mechanism may be arranged to fold them differently if so required. Thus the first fold, instead of being parallel to the sides of the square of paper, may be diagonal therewith and the second fold at right angles to the first.

I do not desire to be confined to the exact construction of the machine or of the mechanism for operating the several folding blades, or other moving parts, but claim broadly the means described for imposing the required folds on a paper serviette.

Having now particularly described my invention, I hereby declare that what I claim as new and desire to be protected in by Letters Patent, is:

1. In a machine for folding paper, the combination with a plane fence having an elongated pocket which is provided with an opening or slot, a reciprocating blade for folding the paper sheet through the slot into the pocket, said pocket having a slot through the same in a plane at right angles to the plane of the pocket, a movable folding blade, means for passing said folding blade

rectilinearly endwise into and bodily edge-wise along through said pocket slot to effect a second fold in the folded sheet of paper and carry the paper along, and means for maintaining said blade to move bodily along through said slot with its paper engaging edge normal to the line of movement, 70

2. A machine for folding paper, the combination with a plane fence having an elongated pocket provided with an opening or slot, a reciprocating blade for folding the paper sheet through the slot into the pocket, said pocket having a slot through the same in a plane at right angles to the plane of the pocket, a uni-directionally movable folding blade, means for passing said folding blade through said pocket slot to effect a second fold in the folded sheet of paper and carry the paper along, a guideway along which said paper is carried, a triangular 80 blade for holding said paper when it arrives at a predetermined place and other folding blades co-operative with said holding blade to effect the final folds of the sheet.

3. A machine for folding paper, comprising the combination of a plane fence having a slot across its middle and walls extending backwardly from the edges of the slot at right angles to the face of the fence, the 95 walls of said slot having a slot across the middle of them at right angles to said walls and to the plane of the fence, said second slot walls having walls projecting at right angles thereto adjacent to the sides of the 100 slot, means for feeding a sheet of paper onto the face of the fence, a blade edgewise movable into the slot of the fence, means for endwise moving the blade to carry the paper into its slot and fold it in halves, a plurality of uni-directionally movable blades and means for effecting the travel of said blades into said second slot across the walls of the first slot to carry into said second slot the 110 half folded sheets of papers to impose a 110 quarter fold in the same, substantially as shown and described.

4. A machine for folding paper, comprising the combination with a plane fence, of means for feeding a sheet of paper to it, 115 means for imposing a half fold and a quarter fold upon the sheet, means for folding the outer angular portions of the quarter folded sheet over the central portion, said means comprising the combination with a slotted body into which the quarter folded sheet of paper is delivered, said slotted body having a triangular notch removed from its upper and lower sides corresponding approximately to the form of the folded paper required, a triangular folding blade pivotally mounted on each side of the notch and adjacent the apex, said blades movable across the notch in planes parallel and adjacent the plane of the slot, a presser blade shaped to 125 130

- conform to the notch movable back and forth into and from it, means for lifting the presser blade at the outer limit of its movement above the plane of the paper in 5 the slot, means for depressing the presser blade at the inner limit of its movement to carry the middle portion of the quarter folded sheet below the plane of the angular folding blades, and means for moving the 10 angular folding blades across the middle portion of the quarter folded paper to fold the outer angular portions of it over the middle portion. 70
5. A machine for folding paper comprising the combination with a plane fence having a first fold slot across its middle, of walls extending backwardly from the edges of said slot, said walls having a second fold slot across the middle, and walls extending 20 from the edges of said second fold slot, said last named walls having an angular notch or recess, the axis of which is at approximately 45° from the end of the slot walls farthest from said second fold slot, means 25 for rigidly supporting a roll of paper over the plane fence, means for cutting a sheet of paper from the roll when it is on the plane of the fence, a first fold blade slidably mounted to move toward the plane fence into the slot thereof, means for projecting and withdrawing said blade, a second blade movable through the slot in the 30 backwardly extended walls, means for operating said last named blade to carry the initially folded sheet into the second fold slot and to transfer it to the end of the second fold slot walls, a presser blade movable back and forth into said angular notch or 35 recess, means for depressing said presser blade at the inner limit of its movement below the plane of the slot, and means for folding the outer corners of the quarter folded sheet over the edges of the presser blade, means for withdrawing said presser blade, 40 and means for elevating the same at the outer limit of its movement. 45
6. A machine for folding paper, comprising the combination with a plane fence having a slot across its middle and walls extending from the edges of the slot at right angles to the plane of the fence, of means for delivering a sheet of paper across the plane of the fence, a blade for folding the sheet through said fence slot to project between 50 said walls, said walls having a transverse slot, a paper folding blade movable through said transverse slot, means for projecting said blade into said transverse slot, moving it through it and withdrawing it therefrom, said means comprising a plate frame secured to the frame of the machine in a plane parallel to and adjacent said transverse slot, said plate having a groove in it formed as a rectangle, a square die movable in the rectangular groove on which die the last named blade is secured, an endless chain mounted on corner sheaves to move around a rectangle similar to that of the groove and in a plane parallel to it, means secured to the chain for engaging the die and moving it around the rectangular groove, and means for driving 55 the chain. 107
7. A machine for folding paper, comprising the combination with a plane fence having a slot across its middle and walls extending from the edges of the slot at right 60 angles to the plane of the fence, of means for delivering a sheet of paper across the plane of the fence, a blade for folding the sheet through said fence slot to project between said walls, said walls having a transverse slot, a paper folding blade movable through 65 said transverse slot, means for projecting said blade into said transverse slot, moving it through it and withdrawing it therefrom, said means comprising a plate frame parallel to and adjacent said transverse slot, said plate having a groove in it formed as a rectangle, a square die movable in the rectangular groove on which die the last named blade is secured, an endless chain movable 70 in the groove and in a plane parallel to it, means secured to the chain for engaging the die and carrying it around the rectangular groove, and means for driving the chain. 75
8. A machine for folding paper, comprising the combination with a plane fence having a slot across its middle and walls extending from the edges of the slot at right angles to the plane of the fence, of means for delivering a sheet of paper across the plane of the fence, a blade for folding the sheet through said fence slot to project between 75 said walls, said walls having a transverse slot, a paper folding blade movable through said transverse slot, means for projecting said blade into said transverse slot, moving it through it and withdrawing it therefrom, said means comprising a plate frame parallel to and adjacent said transverse slot, said plate having a groove in it formed as a rectangle, a square die movable in the rectangular groove on which die the last named blade is secured, an endless chain movable 80 in the groove and in a plane parallel to it, means secured to the chain for engaging the die and carrying it around the rectangular groove, and means for driving the chain. 85
9. A machine for folding paper, comprising the combination with a plane fence having a slot across its middle and walls extending from the edges of the slot at right 90 angles to the plane of the fence, of means for delivering a sheet of paper across the plane of the fence, a blade for folding the sheet through said fence slot to project between said walls, said walls having a transverse slot, a paper folding blade movable through 95 said transverse slot, means for projecting said blade into said transverse slot, moving it through it and withdrawing it therefrom, said means comprising a plate frame parallel to and adjacent said transverse slot, said plate having a groove in it formed as a rectangle, a square die movable in the rectangular groove on which die the last named blade is secured, an endless chain movable in the groove and in a plane parallel to it, means secured to the chain for engaging the die and carrying it around the rectangular groove, and means for driving the chain. 100

- angles to the plane of the fence, of means for delivering a sheet of paper across the plane of the fence, a blade for folding the sheet through said fence slot to project between said walls, said walls having a transverse slot, a paper folding blade movable through said transverse slot, means for protecting said blade into said transverse slot, moving it through it and withdrawing it therefrom, said means comprising a plate frame secured to the frame of the machine in a plane parallel to and adjacent said transverse slot, said plate having a groove in it formed as a rectangle, a square die movable in the rectangular groove, said die having a square shoulder the sides of which are disposed diagonally in relation to the sides of the die on the upper side of which the last named blade is secured, an endless chain mounted on corner sheaves to move around a rectangle similar to that of the groove and in a plane parallel to it, means secured to the chain and projecting across the groove to engage a corner of the square shoulder of the die, and means for driving the chain.
10. In a paper folding machine, a slotted folding member, means for projecting a paper folding blade into said slotted folding member, carrying it through the slot into which the paper is folded, and withdrawing it therefrom, said means comprising the combination with a plate having a groove in its surface disposed as a rectangle in a plane parallel to that of the slot, a chain movable in a parallel plane around a similar rectangle, a square die fitting the groove said die having a square projection from it
- the sides of said projection being disposed diagonally in relation to the sides of the groove fitting portion of the die, a fitting strip adjustably secured on each diagonal side of the die projection, and a driving plate secured to the chain and projecting across the groove to engage the corners of the fitting strips.
11. In a paper folding machine, the combination with a fence having a slot across the same and parallel walls forming a pocket in back of said slot, of means for delivering paper from a roll onto said fence, means for cutting said paper delivered from the roll to the fence, a reciprocating blade for initially folding the paper through said slot into said pocket, said pocket forming walls having transverse alining slots, other walls registering with said alining slots for receiving the paper when folded the second time, uni-directionally movable folding fingers passing through said pocket slots to effect a second fold in the sheet and carry the sheet along between said second mentioned walls, means for endwise withdrawing said fingers from the folded sheet, a holding member for engaging the folded sheet when it arrives at the limit of its movement under the influence of said fingers and other folding devices coöperating with said holding member for effecting the final folds of the paper.
- In testimony whereof I affix my signature in presence of two witnesses.

AARON GROFF.
